UNITED STATES PATENT OFFICE.

GEORGE A. OWEN, OF HARTFORD, AND GEORGE A. BATES, OF NEW BRITAIN,
CONNECTICUT.

HYDRANT AND REEL.

1,079,717.

Specification of Letters Patent.

Patented Nov. 25, 1913.

Application filed May 5, 1913. Serial No. 765,528.

To all whom it may concern:

Be it known that we, GEORGE A. OWEN and GEORGE A. BATES, citizens of the United States of America, and residents of Hartford and New Britain, respectively, in the county of Hartford and State of Connecticut, have invented certain new and useful Improvements in Hydrants and Reels, of which the following is a full, clear, and 10 exact description.

This invention relates particularly to improvements in hydrants such as used for fire purposes, that are located near the sidewalk curbing of streets, and have valve connections in their lower portions below the ground to receive water under considerable pressure from the normal or special high pressure water main.

The object of our present invention is to 20 provide an attachment in the form of a rotatable casing or reel mounted to turn on a vertical axis at the top portion of the hydrant casing, for purpose of carrying a coil of hose; and which in both the wound 25 position in the receptacle, and in the unwound or stretched position is connected or coupled to the hydrant casing for use, so that by merely pulling on the hose to unwind it, and then opening the water valve 30 at the lower portion of the hydrant casing, the apparatus is ready for use.

In the accompanying drawings illustrating one embodiment of our invention,—Figure 1 shows the upper, or above-ground 35 portion of the hydrant. Fig. 2 is a vertical axial section of the device as shown in Fig. 1. Fig. 3 is a horizontal section on the line 3—3, of Fig. 2; and Fig. 4 shows enlarged one of the door hinges.

In the drawing, 6 represents the upper or 40 the above-ground portion of a hydrant casing, that it will be understood, is provided with some kind of a valve arrangement in its lower portion, having operating means 45 such as a shaft 7 carrying a gear 8 meshing with a gear 9 that can be turned by a crank handle 10 at the side of the casing; but such construction forms no part of the present invention, and any desired form of valve 50 controlling means may be employed.

The upper end portion of the casing 6 is provided with a reduced extension 12 of cylindrical form, that is connected with the casing by a shoulder portion 13; and the 55 top of the extension 12 is shown as closed by

an end member 14; the cylindrical side wall of the extension being provided with a series of ports 15.

A cap member 16 is shown having its cylindrical bore rotatably engaging the extension 12 and provided with a flange 17 at the base resting on the shoulder portion 13 of the casing; the top of the cap member being closed by a portion 18. The side of the cap 16 is provided with a port 19 at 60 which is secured a hose coupling 20 for connection with a line of hose 21 of any desired form.

It will be understood that the port 19 of the cap member will at all times register 70 with one of the ports 15 of the casing, so that the hose is always in communication with the interior of the hydrant casing to receive the water when the valve is opened through the controlling stem 7.

The hose 21 will be wound around the cap member 16 when it is turned by suitable means, such as a crank handle 22, and to support the hose we provide a receptacle in the form of a shell 23, consisting of a bottom member 24 suitably secured to the hydrant casing 6, being shown as bolted to a flanged sleeve 25, that is bolted to the casing outside of the shoulder portion 13; the bottom 24 having a central opening surrounding the cap 16; and the sleeve 25 having an internal flanged portion 26 engaging the upper face of the flange 17 at the base of the cap 16, whereby the cap member is secured in its rotative position.

The shell 23 has a cylindrical side portion 27, forming an annular chamber with the cap member for receiving the hose 21 in its wound-up position, as shown in Fig. 3.

A suitable closure is provided at the top 95 of the side portion 27 of the shell, such as a removable lid 28 shown in the form of a cone, having a cylindrical flange portion 29 at the bottom fitting over the side portion 27 of the shell at its top.

The side portion 27 of the shell is provided with an opening at 30 through which the end of the hose 21 is passed, and then the hose can be pulled through said opening to unwind it, thereby rotating the cap member 16, until the hose is entirely unwound except the end portion that will remain connected at the coupling 20.

At the opening 30 is provided a suitable door 31 connected with the shell by hinges 110

32 and 33, one of which is shown in Fig. 4, as comprising a member 34 secured to the door and a member 35 secured to the side 27 of the shell. These two members have 5 the usual registering apertures for receiving a pivot 36, and the engaging faces 37 and 38 of the hinge member are provided with similar inclined faces 39 and 40 that will serve to return the door to closed position 10 by gravity, from a partly opened position; and which will further serve to retain the door in the closed position, avoiding the necessity of any special door securing means 15 for locking it closed.

15 In the use of the device, it is only necessary to open the door 31, grasp the hose by the nozzle end and pull it out through the opening until it is entirely unwound; whereupon the valve at the bottom of the hydrant 20 can be opened by means of the handle 10, or other means that may be provided for such purpose.

When it is desired to return the hose to the casing, it is only necessary to rotate the 25 cap member by the crank handle 22, and for this purpose the lid is simply removed by lifting it off from the top; the hose will be rewound upon the cap member 16, passing back through the opening at 30 until it is 30 entirely within the shell as indicated in Fig. 3, when the door 31 can be closed, and the lid 28 replaced.

We claim:—

1. In a hydrant, a casing having at the 35 top a reduced tubular extension connected with the casing by a shouldered portion, the extension having the top closed and the sides provided with ports, a cap member rotatable on the extension and provided 40 with a port in the side arranged to register with the said extension ports, the cap having a flange at the base engaging the said shouldered portion of the casing, a shell comprising an annular base secured to the 45 casing with its inner marginal portion engaging the top face of the cap flange to retain the cap in its rotative position, the shell having cylindrical sides opposite the cap sides to form an annular chamber for containing a hose secured at said coupling and wound around the cap, and a removable lid on the casing.

2. In a hydrant, a casing having at the top a reduced tubular extension connected with the casing by a shouldered portion, the 55 extension having the top closed and the sides provided with ports, a cap member rotatable on the extension and provided with a port in the side arranged to register with the said extension ports, the cap having a flange at the base engaging the said shouldered portion of the casing, a crank handle on top of the cap, a shell comprising an annular base secured to the casing with its inner marginal portion engaging the top face of the cap 60 flange to retain the cap in its rotative position, the shell having cylindrical sides opposite the cap sides to form an annular chamber for containing a hose secured at said coupling and wound around the cap, 65 and a removable lid on the casing.

3. In a hydrant, a casing having at the top a reduced tubular extension connected with the casing by a shouldered portion, the extension having the top closed and the 75 sides provided with ports, a cap member rotatable on the extension and provided with a port in the side arranged to register with the said extension ports, the cap having a flange at the base engaging the said shouldered portion of the casing, a crank handle on top of the cap, a shell comprising an annular base secured to the casing with its 80 inner marginal portion engaging the top face of the cap flange to retain the cap in its rotative position, the shell having cylindrical sides opposite the cap sides to form an annular chamber for containing a hose secured at said coupling and wound around the cap, 85 and a removable lid on the casing.

Signed by us in presence of two subscribing witnesses.
